UNITED STATES PATENT OFFICE.

ALFRED J. MORRISON, OF DENVER, COLORADO, ASSIGNEE TO STOKES AND SMITH COMPANY, OF SUMMERDALE, PHILADELPHIA, PENNSYLVANIA, A CORPORATION OF PENNSYLVANIA.

TURN-IN FINGER FOR BOX-COVERING MACHINES.

1,424,316.

Specification of Letters Patent. Patented Aug. 1, 1922.

Application filed December 2, 1920. Serial No. 427,737.

To all whom it may concern:

Be it known that I, ALFRED J. MORRISON, a citizen of the United States, and resident of the city of Denver, in the county of Denver and State of Colorado, have invented certain new and useful Improvements in Turn-In Fingers for Box-Covering Machines, of which the following is a specification.

This invention relates especially to improvements in devices for turning or tucking in the upper edge of a cover applied to a box part. This is an operation usually followed by turning down the edges of the cover against the inner faces of the box wall to complete the covering operation.

Devices heretofore employed for the turning or tucking in operation are called tuck-in fingers or edge-tuck-in fingers. In one well known form they comprise two flat strips of metal arranged near opposite sides of the box part being covered, the strips being slightly shorter than the length of the box side walls, these strips being moved by suitable mechanism toward each other and over the upper edges of the box side walls to turn horizontally inward the upwardly projecting edges of the cover at the sides of the box; and two other fingers arranged opposite the end walls of the box part and provided with suitable mechanism for moving them inward to turn or tuck in the edges of the cover extending up at the ends of the box. To insure a close and tight covering of the box edges both the side and end fingers have been arranged with their lower surfaces, throughout the greater part of their lengths only slightly above the upper edges of the box body. This necessitates the arrangement of the major portions of the end fingers in the same plane as the entire length of the side fingers, and to avoid interference between the end and side fingers, the end portions of the end fingers are offset; that is bent slightly upward and then bent straight outward again, so that these end portions ride over the ends of the side fingers and the main, central portions of the end fingers pass closely over the upper edges of the box ends.

It is necessary with the end fingers so constructed to provide end fingers of approximately correct length for each different width of box to be covered, and especially to arrange the offset bends in the end fingers at the proper positions, to properly co-operate with the side fingers, for each box width. To enable end fingers to be prepared, it has been customary to provide a tool called an embossing press to bend the end fingers to provide the offsets and it is found that in careless use of this tool, or when the end fingers are not formed with proper accuracy by other means, the central portion of the fingers between the offsets is sometimes bent, or for other reasons the offsets are not properly located, or the end portions of the end fingers do not fit closely down upon the ends of the side fingers, which results in a loose corner fold of the tucked-in cover edge. In the subsequent operation of turning the cover edge down and against the inner surfaces of box walls, this loose fold causes a bunched and unsightly formation of the cover at the corners of the box.

Tuck-in mechanism of the class described usually operates in conjunction with a two-part plunger which is inserted in the box part, and when the tuck-in operation is to be performed the upper plunger section is withdrawn sufficiently to permit the edges of the cover to be tucked in as described. After the fingers are withdrawn the upper plunger is moved down into the box part to turn the cover edges down against the inner surfaces of the box walls and thereafter suitable pressing devices act against the box walls in co-operation with the plunger.

A principal object of my invention is to do away with the annoyance and expense incident to the provision of offset end fingers and also to avoid the production of loose or imperfect corner folds consequent upon the use of improperly formed offset fingers, as above described, and at the same time to provide simplified end fingers which do not have to be specially shaped or cut to special length for different widths of boxes, within reasonable limits.

Another object is to provide for the

proper relation of the tuck-in devices to other parts of the covering mechanism, such as a two-part plunger above mentioned.

To attain these and other objects my invention comprises substantially straight end tuck-in fingers having their inner lower edges beveled so that the end fingers may be arranged to move very nearly in the same plane as the side fingers, and the edge bevels 5 cause the ends of the end fingers to ride up over the ends of the side fingers and grip the cover edge between the adjacent surfaces of the fingers and make an accurate, tight fold; so that after the fingers are withdrawn 10 and the plunger turns the cover edges down into the box the corner folds fit perfectly into the box corners without bunching or lumping of the cover sheet. These end fingers may co-operate with side fingers of 15 ordinary form. The tuck-in fingers so constructed and arranged, are arranged to co-operate with two-part plunger mechanism as sufficiently described hereinafter.

In the foregoing and later description the reference to certain fingers as end fingers 20 and other fingers as side fingers is only for convenience in identification of different parts; and although in the actual embodiment of the invention it is usually convenient to arrange the straight beveled fingers to co-operate with the ends of the box, evidently this is not essential, and the terms "end" and "side" may be interchanged without in any way affecting the principles 25 involved.

The accompanying drawing shows one exemplifying embodiment of the invention and after considering this, persons skilled in the art will understand that variations 30 may be made within the principles of the invention and I do not limit myself to details, except as claimed.

In the drawings:

Fig. 1 is a top plan of tuck-in fingers embodying the invention, shown in connection with sufficient parts of their supporting and operating mechanism and in operative relation to a box part.

Fig. 2 is a vertical longitudinal section 45 of the mechanism shown in Fig. 1 with the added showing of a two part plunger in dotted lines.

Figs. 3 and 4 are fragmentary views of one corner of a box part and cover paper, 50 with adjacent fragments of tuck-in fingers in different operative positions.

Figs. 5 and 6 are fragmentary perspective views of a corner of a box part and its cover paper in different conditions.

60 A box part B having side walls 10 and end walls 11 and a bottom 12, and open at the top, is supported in different covering operations by a two-part plunger P, Fig. 2, comprising a lower section 15 and upper section 16 of identical horizontal outline,

arranged to fit quite closely within the box part and provided respectively with operating stems or plungers 17 and 18, the plunger 17 usually being arranged movably within the hollow plunger 18, and suitable operating mechanism being provided so that the upper and lower plunger may be moved together or separately.

The box part is shown in all the figures provided with a covering sheet C, usually 75 of paper, which has been applied by previous operations of the machine to the bottom, side and end walls of the box part, leaving edge portions 20 of the cover projecting above the upper edges of the box walls 80 throughout the circumference of the box, these edge portions usually having side or end laps 21 at one or more corners of the box, these end laps producing corner folds 22.

85 Adjacent to the side walls of the box are side tuck-in fingers 30 consisting of straight flat strips of metal of a length just slightly less than the length of the box. The lower surfaces of these fingers are arranged very 90 slightly above the level of the upper edges of the box walls when the box part is in position for the tuck-in operation.

95 Arranged adjacent to the end walls of the box are end tuck-in fingers 35, usually straight flat strips of metal which may be of any convenient length slightly or considerably longer than the length of the ends of the boxes to be covered. The lower inner edges of fingers 35 are provided with beveled surfaces 37 extending at least a considerable distance along each strip near its ends and more conveniently extending throughout the length of each strip. The end fingers are arranged with the front edges 100 of the bevels 37 slightly above the level of the ends of side fingers 30, so that in the inward movement of the end fingers their bevels ride up over the ends of the side fingers 30, avoiding any conflict between the 105 side and end fingers, and this arrangement at the same time brings the lower surfaces of the end fingers very close to the level of the upper edges of the box ends.

110 Each finger 30 and 35 is carried by a head 40 connected to suitable supporting and operating rods 41, or the heads may be provided with ears or clevises 42 for the reception of suitable operating levers or links; and suitable mechanism is provided for first moving 115 the side fingers 30 simultaneously across the upper edges of the box to fold horizontally the side edges 20 of the cover paper and then to move the end fingers 35 simultaneously across the ends of the box and across the 120 ends of the side fingers to fold inward the end edges 20 of the cover and in this operation the corner fold 22, as shown in Fig. 4, is pressed smoothly down over the ends of the side fingers, leaving the box and cover, 125 130

when the fingers are withdrawn, in the condition shown in Fig. 5.

Previous to the tuck-in operation the upper plunger 16 is withdrawn to the position shown in Fig. 2, or somewhat higher than that position, the lower plunger 15 remaining at the bottom of the box part. After the tucking in operation and the withdrawal of the fingers the plunger 16 is moved down into engagement with the plunger 15 and in this movement the edges 20 of the cover are smoothed down against the inner faces of the box walls and the corner folds 22 are forced smoothly into the corners 15 of the box, as clearly shown in Fig. 6, without bunching or wrinkling. The smooth final arrangement of the corner fold is due to the accurate and firm creasing provided by the beveled end fingers.

To provide for ready insertion and removal of the fingers heads 40 may be laterally slotted to provide upper and lower jaws 50, 51, between which the fingers are inserted. A screw 52 passes through suitable holes in upper jaw 50 and in the finger and engages a threaded hole 53 in the lower jaw 51 so that the jaws may be quickly clamped upon the finger. Details of the holding and operating devices may evidently be varied greatly.

It is evident, especially from an inspection of Fig. 1 that since the beveled edges of fingers 35 cause them to ride over or overlie the ends of the side fingers, the end fingers 35 may be made as long as desired within reasonable limits, and, therefore, the same end fingers may be used for boxes of greatly varying widths. The expense and annoyance of cutting the end fingers to special lengths is, therefore, reduced or entirely eliminated. The described construction of the end fingers also enables them to be made straight and flat, without offsets, such as are required in other forms of end fingers as previously mentioned. Therefore, the inconvenience and expense involved in providing the offset bends in such fingers and the expense involved in providing an embossing or offsetting machine, and also the liability to produce improperly formed offset fingers, and the operative difficulties and annoyances incidental to such improperly formed fingers, are avoided.

What I claim is:—

1. In a box covering mechanism, a first pair of oppositely-acting tuck-in-fingers adapted to overlap and co-operate with a second pair of fingers throughout a substantial range of variations in the spacing of said second pair.

2. In a box covering mechanism, a first pair of oppositely-acting tuck-in-fingers adapted to co-operate with a second pair of fingers throughout a substantial range of variations in the spacing of said second

pair, the fingers of said first pair having inward and downward presented beveled faces co-operating with the ends of the fingers of said second pair.

3. In box-covering mechanism of the class 70 described, tuck-in-fingers adapted for operation upon boxes of varying widths in co-operation with other fingers of lengths suited to the length of the box operated on, consisting of metal strips substantially 75 longer than the width-range of boxes to be operated on.

4. In box-covering mechanism of the class 80 described, tuck in fingers adapted for operation upon boxes of varying widths in co-operation with other fingers of lengths suited to the length of the box operated on, consisting of metal strips substantially longer than the width range of boxes to be operated on, said strips having inward and 85 downward presented beveled faces.

5. In box part covering mechanism, a pair of opposite tuck-in fingers and another pair of opposite co-operating tuck-in fingers having beveled surfaces arranged to co- 90 operate with portions of the fingers of the first mentioned pair.

6. In box part covering mechanism, a pair of opposite tuck-in fingers and another pair of opposite substantially straight and flat 85 tuck-in fingers of a length sufficient to overlap the fingers first mentioned and having beveled lower inner faces to co-operate with the fingers first mentioned to produce a close corner fold in the inturning of the upper 100 edge of a box cover paper.

7. In box covering mechanism comprising a two part plunger to support a box part during covering operations and means for moving the plunger parts, two opposite 105 side tuck-in fingers arranged to move closely over side edges of the box part and two substantially straight, flat end tuck-in fingers arranged to move closely over the end edges of the box part, the end fingers 110 being provided with inwardly and downwardly presented beveled surfaces to co-operate with the ends of the side fingers in tucking in the upper edges of the box cover paper and forming corner folds of 115 the tucked-in edges.

8. In box covering mechanism comprising a two part plunger to support a box part during covering operations and means for moving the plunger parts to withdraw the 120 upper plunger while the lower plunger remains within the box part during a tuck-in operation, two opposite side tuck-in fingers arranged to move closely over side edges of the box part and two substantially straight, 125 flat end tuck-in fingers arranged to move closely over the end edges of the box part, the end fingers being provided with inwardly and downwardly presented beveled surfaces to co-operate with the ends of the 130

side fingers in tucking in the upper edges of the box cover paper and forming corner folds of the tucked-in edges.

9. A tuck-in finger for box covering mechanism, consisting of a strip having a beveled operating edge to co-operate with other tuck-in fingers.

10. A tuck-in finger for box covering

mechanism consisting of a substantially straight flat strip having a beveled edge 10 adapted to co-operate with end portions of complementary tuck-in fingers.

Signed at city of Denver, in the county of Denver, and State of Colorado this 17th day of November, A. D. 1920.

ALFRED J. MORRISON.
